UNITED STATES PATENT OFFICE

FRANK A. PESCHL, OF JACKSON HEIGHTS, NEW YORK

PAPER-MAKING MACHINE

Application filed December 24, 1927. Serial No. 242,306.

This invention relates to paper making machines, and is concerned more particularly with the formation and manipulation of the so-called "lead strip," which is a strip formed on one edge of the paper web to facilitate the initial feed of the web through the machine when the machine is started up, or to reestablish the feed of the web in the event of the accidental breakage or parting of the same.

In the U. S. Patent No. 1,634,885 granted to me on the 5th day of July, 1927, there is disclosed a mechanism as an attachment for paper making machines, operable in the event of an abnormality or defect in, or the accidental parting or breaking of the paper web at any point in the machine, to bring into action an air jet to cause a break in said web at a point in the machine preceding the accidental breaking point, so as thereby to interrupt and prevent the further feed of the web into the machine until the waste paper or so-called "broke" has been removed and the lead of the paper web through the machine has been reestablished. Such reestablishment of the feed of the web is usually effected by forming on the paper web, a lead strip and tendering this lead strip through the machine, and after the strip is feeding properly, the relatively narrow strip is widened out to the full width of the web. The formation of such lead strip may be effected in various ways, such as by incising the sheet at one edge with a cutter or knife, or when the lead strip is formed at a point in the web where the stock is soft, as where the web is still on the forming wire or between the forming wire and first press, the incising of the web may be effected by a water jet or an air jet, directed downwardly on the moving web, which air jet by being moved transversely across the machine will act to widen out the lead strip to the full width of the paper web.

It has been found in the practical operation of the machines that the accidental parting or breaking of the web takes place in most cases in the drier section, and considerable difficulty has been encountered on the part of the workmen in entering the lead

strip and starting its travel through the presses, which difficulty is more pronounced in connection with the third or reversed press where the paper has to make a sharp reverse turn before entering the press.

The present invention aims to overcome this difficulty and to relieve the workmen entirely of the necessity of the manual handling of the lead strip in entering the same in the presses, or in other parts of the machine preceding the point of the accidental break; and the invention consists of means adapted to be brought into action by the accidental parting of the web, and operating to form a lead strip on the paper web, before the automatically operating mechanism has broken the web entirely across, the result being that the portion of the web constituting the lead strip, will continue uninterruptedly through that portion of the machine which precedes the point of accidental break, so that it will not be necessary for the attendant, as heretofore, to manually start the lead strip, for instance, through the presses, in the event that the web accidentally breaks in the driers or at a point beyond.

In its more specific embodiment, the invention in carrying out this object, involves a water jet located in the machine adjacent and preceding the point where the air jet starts the breaking of the web, and directed so as to discharge normally beyond the edge of the web, which water jet is movable so that it may be adjusted to discharge onto the web, and means are provided operated automatically when the air jet is turned on to break the web, to move the water jet inwardly so that it will impinge on the web adjacent its edge, the result being that the water jet will form an incision in the web which will prevent the break started by the air jet, from developing entirely across and completely severing the web.

In the specification to follow the invention will be described in detail, and the novel features thereof will be set forth in the appended claims.

Referring to the drawings

machine as will be necessary for an understanding of the invention, the same having the invention embodied therein.

Fig. 6 is a plan view of a paper web which has accidentally broken in the drier section of the machine, showing a lead strip formed thereon and widened out to the full width of the web.

Fig. 7 is a plan view of a modified form of the mechanism for controlling the action of the water jet by which the lead strip is formed.

Fig. 8 is a side elevation of the same.

Fig. 9 is a cross section on the line 9—9 of Fig. 7 as viewed in the direction of the arrow on said figure.

In the accompanying drawings

Referring to Figs. 1 and 2, there are illustrated in a paper making machine, the forming wire 1, couch roll 2 at the delivery end of the forming wire, the first press 3 to which the paper web 4 passes from the forming wire, the second and third presses 5 and 6 to which the web passes in succession from the first press, and drier cylinders 7 receiving the web from the third press, but three of the drier cylinders being shown.

There is diagrammatically shown associated with these parts of the machine, the mechanism A of my Patent No. 1,634,885 hereinbefore referred to and adapted to cause a break in the paper web between the couch roll and first press felt and thereby interrupt the feed of the web upon the accidental parting of the web at a point beyond, the said mechanism comprising an air jet nozzle or pipe 8 arranged to deliver its jet onto the central portion of the soft web at a point between the couch roll and first press felt, so as to start a break in the web, a valve 9 to control said jet, and operated by a solenoid core and coil 10 in a power circuit 11 from which, branch conductors 12 lead to contactors 13 located at different points in the machine, the said contactors being adapted to be operated to close the circuits upon a break of the paper web occurring at any of said points, and when so operated, opening the valve 9 and permitting a jet of air to impinge on the paper web, all as described in detail in said patent, to which reference may be had for a fuller description than is here given.

In the operation of said mechanism, the closure of the power circuit by any one of the contactors on the breakage of the web, will

open the valve 9, and air under pressure issuing from the nozzle 8 in the form of a jet will impinge upon the soft web and will rupture the same as shown at 14 in Fig. 2, and the rupture quickly spreading transversely will sever the web throughout its width, whereupon the web instead of passing forwardly into the first press will pass down around the couch roll into a save-all, whence it is returned to the stock box. When after such action the "broke" is cleared away at the point where the accidental parting of the web occurred, and the machine is ready to resume operations, a lead strip is formed on the paper web on the forming wire by means of a squirt nozzle as shown in Figs. 3 and 4, in the form of a depending pipe or nozzle 15 connected to a length of hose 16 seated and movable in a fixed transversely extending horizontal guide trough 17 supported on the upper ends of standards 18 extending upwardly from the frame of the machine. The hose being supplied with water, the latter issues as a jet from the nozzle 15, and by pushing or pulling endwise on the hose, the attendant can position the nozzle at the desired point in the width of the paper web. In forming the lead strip, under such previous practice, the attendant drew the nozzle from its inactive position as shown in Fig. 3, to the position shown in said figure by dotted lines, thereby causing the jet to strike the web a short distance from its edge. The nozzle was held in this position until the lead strip formed by the incising effect of the jet, was feeding through the machine, whereupon, the nozzle was pushed back to its former position, thereby widening the lead strip to the full width of the web.

The present invention is shown, in the particular embodiment of the same illustrated by way of example, as applied in connection with the mechanism above described, and comprises a water jet nozzle 19 depending from a horizontal water supply pipe 20 and connected therewith by a jointed coupling 21 as best shown in Fig. 3, so that the nozzle can be swung from its inactive full line position shown in said figure, inwardly to its active dotted line position, the nozzle when in its inactive position discharging into a fixed deflecting spout 22 positioned to direct the water beyond the edge of the paper web, and when in its active position, discharging onto the paper web at a point near the edge of the same so as thereby to form a lead strip on the paper web.

The nozzle 19 is swung inwardly to active position to thus squirt on the web, by means which are brought into action upon the opening of the valve 9 controlling the flow of air to the air jet nozzle 8, which means in the present form of the invention is in the form of an air cylinder 23 and a piston 24 therein having its piston rod 25 jointed to a link 26

clipped to the nozzle 19, the cylinder being supplied with air from the air supply pipe by which the jet 8 is supplied, as by a branch 27 as best shown in Fig. 1.

- 5 Due to the form and arrangement of the parts described, when, with the nozzle in the position shown in full lines and discharging into the spout, the valve 9 is opened upon the accidental breakage of the paper web, and the 10 air jet from nozzle 8 starts the break of the web the air flowing through pipe 27 will move the piston 24 in its cylinder, and the water jet nozzle 19 will be swung inwardly to active position, thereby impinging its jet on 15 the paper web near its edge and forming the lead strip thereon.

As a result of the impingement of the water jet from nozzle 19 on the paper web at a point on the forming wire a short distance

- 20 preceding the point where the air jet from nozzle 8 impinges, the cut made in the web by the water jet will prevent the rupture made by the air jet from developing at the front side of the web beyond said cut and 25 thus will prevent the complete severance of the web. Consequently the lead strip will be maintained on the web and will be carried with it into the presses, so that there will be no necessity for the manual handling of the 30 strip by the attendants as heretofore practised in entering the lead strip in the presses.

The lead strip being thus automatically started at the instant of the rupture of the web by the air jet, it remains for the operator to widen out the strip to the full width

- 35 of the web, when the travel of the lead strip through the machine has been established after the removal of the "broke" at the point where the accidental parting of the web took place. In the present instance this widening 40 of the lead strip is effected by the water squirt nozzle 15, which, when the lead strip is to be widened out, is drawn to the front by the attendant until the water squirt hits 45 the cut defining the lead strip, whereupon the water squirt is pushed rearwardly across the paper web to its former position, thereby cutting the same across on a line as at 28, which line, due to the travel of the web relative to the fixed point of impingement of the 50 water jet, will extend obliquely to the web as shown in said figure. The lead strip by this operation will, as shown in Fig. 6, be widened out until it takes in the entire width 55 of the paper web, and being carried forward by the lead strip, the reestablishment of the feed of the web will be effected.

Means are provided, which, when the water squirt nozzle has been drawn forwardly by the attendant to effect a widening of the lead strip as described, will act automatically to swing the water jet nozzle 19 to inactive position so that it will discharge into the deflecting spout, which means in the present case 60 is in the form of a horizontal arm 29 fixed to

and extending forwardly from the nozzle 15 just below the guide trough 17. This arm is adapted, when the nozzle 15 reaches a point where the squirt is coincident with the cut defining the lead strip, to engage a horizontal 70 arm or lug 30 on the piston rod 25, and by such engagement the piston rod will be pushed toward the front of its cylinder, and the water jet nozzle 19 will be swung to its full line active position to discharge into the 75 deflecting spout. It will be understood therefore that by this action of the parts, the movements of the water squirt nozzle toward the front by the attendant, will automatically 80 cut off the action of the lead strip forming jet.

The inner active position of the nozzle is determined by a fixed stop 301; and its outer inactive position by a stop 302.

It will be understood that other means than those described may be employed for swinging the water jet nozzle 19 inwardly to active position, such for instance as the means shown in Figs. 7, 8 and 9, wherein electrically operated mechanism, actuated by the power circuit controlling the valve 9 of the web rupturing mechanism, are illustrated to accomplish this result, instead of the pneumatic means shown in Figs. 1 to 5.

On reference to Figs. 7, 8, and 9 it will be seen that the nozzle 19^a is clipped to a horizontal shaft 31 mounted to rock in bearings 32 supported by a suitable frame 33 sustained by the machine framing at its front. A ratchet wheel 34 is supported on the shaft and is held frictionally engaged therewith to permit circumferential relative movement thereon, by being seated against a flange 35 on the shaft and held frictionally thereagainst by a rubber block 36 compressed between inner and outer washers 37 and 38 splined on the shaft and confined by nuts 39 screwed on the shaft, the inner washer bearing against the side of the ratchet wheel and holding the same frictionally against the flange 35. As a result of this form and construction of the parts, while the motion of the ratchet will be transmitted to the shaft, yet the shaft may be turned independently of the wheel, the purpose of which will presently 100 appear.

The ratchet wheel is engaged by a ratchet dog 40 fixed to one end of a link 41 whose opposite end is pivoted to the upper end of an armature 42 pivoted at its lower end to the frame 33. The armature is acted on by an electromagnet 44 supported by the frame 33 and supplied with current from the power circuit of the web rupturing mechanism hereinbefore described, so that, on the closure of said circuit, upon the accidental parting of the paper web, the electromagnet 44 will be energized and attracting the armature 42, the ratchet dog will be actuated and the ratchet wheel turned, which action will swing the 110 120 125 130

nozzle 19^a to its active position to impinge its jet on the paper web. On the opening of the power circuit when the rupturing mechanism is reset as described in my patent hereinbefore referred to, the armature will be caused by a weight 42^a thereon to swing away from the magnet, and will thereby move the ratchet dog idly over the teeth on the ratchet wheel for a new grip thereon.

10 It will be understood that the nozzle 19^a in this form of the mechanism, is adapted to be swung to its inactive position by the movement of the water squirt 15 toward the front as in the first instance described, the arm 29 on the squirt nozzle being adapted to engage a lug 30^a carried by the nozzle 19^a, when the squirt nozzle reaches a position where its squirt will strike the cut defining the lead strip. Such movement of the nozzle 19^a will 15 be permitted notwithstanding the engagement of the ratchet dog with the teeth of the ratchet wheel and with the magnet energized; by reason of the frictional engagement of the ratchet wheel with the shaft 31 as before described, the shaft turning within the ratchet wheel as the former is rocked when the nozzle 19^a is swung out of action.

The inner active position of the nozzle 19^a is determined by stop 301^a, and its outer inactive position by a stop 302^a, which stops are fixed to an arm 45 depending from the frame 33; and the nozzle is held yieldingly in its inactive position to prevent its accidental displacement from vibrations of the machine, 35 by a spring 303^a attached thereto and to the frame 33.

The operation of the improved mechanism is as follows:

With the machine operating normally, the 40 several branch circuits will be open at the open contactors, the valve 9 will be closed, the water squirt nozzle 15 will be at the far side of the web, the piston 24 will be in retracted position in its cylinder, and the water jet nozzle 19 will be in its inactive position discharging into the deflecting spout 22. When under these conditions, the paper web accidentally parts, say in the drier section, the contactor at that point closing and closing 45 the power circuit, the solenoid controlling the valve 9 will be energized and the valve will be opened. This will cause an air jet from the nozzle 8 to impinge upon the soft paper web, and the latter will be ruptured at the middle portion thereof as shown in Fig. 2. Upon the opening of valve 9, air 50 will flow by pipe 27 to air cylinder 23 and the piston therein will be moved and will swing water jet nozzle 19 inwardly from its inactive position to its active position, thereby causing its water jet to impinge on the paper web near the front edge of the latter and starting the formation of a lead strip. Due to the forward travel of the web, the 55 break started by the rupturing air jet will

develop on an oblique line which will be intersected by the cut defining the lead strip, so that the web will be prevented from breaking clear through, and the lead strip will continue on intact and will pass into the presses, but the remaining portion will pass down between the couch roll and press felt into the save-all, as described in my patent hereinbefore referred to.

The attendant, after the rupture of the web to start the break, closes a cut off valve 9^a placed in the pipe supplying air to the air nozzle and air cylinder, with the result that the air jet from nozzle 8 will be shut off, and the entrapped air in the air cylinder will hold the water jet nozzle 19 in its active position so as to maintain the action of the water jet in continuing the formation of the lead strip. When now the "broke" has been cleared away and the machine is ready to resume operations, the lead strip which has in the meantime been passing through the presses and to waste at the point where the accidental break in the web occurred, is tendered by the attendant to continue its course through the machine, and when the feed of the lead strip has been fully established, the attendant draws the water squirt nozzle 15 toward the front of the machine, which action will swing the water jet nozzle 19 to its inactive position and thereby stop the formation of the lead strip, and the water squirt will strike the cut in the paper web defining the lead strip, whereupon the water squirt nozzle is pushed back across the web to its former position, thereby cutting the web transversely and widening out the lead strip to the full width of the web. The web will now be carried forward by the feed of the lead strip, and the feed of the web through the machine 105 will be reestablished and the normal operation of the machine will be resumed. The passage through the machine of the web will open the conductors, which will open the power circuit, and the attendant will then 110 reset the automatically operating mechanism A so that it will be ready to function in the event of another breakage of the web.

In the foregoing description and accompanying drawings I have set forth my invention in the particular detailed form and construction of the parts which I prefer to adopt. It will be manifest, however, that these details may be variously changed without departing from the spirit of the invention; and it will be understood that the invention is not limited to any particular form or construction of the parts except in so far as such limitations are specified in the claims.

Having thus described my invention, what I claim and desire to secure by Letters Patent is:

1. In a paper making machine, the combination of means for interrupting the feed of the paper web at one point in the machine

- and adapted to be brought into action automatically by an abnormal condition of the paper web at a point in the machine beyond, and web incising means for forming and 5 maintaining a lead strip on the web at the point of interruption of the feed, said last mentioned means being controlled in its action automatically by the feed interrupting means.
- 10 2. In a paper making machine, the combination of means adapted to be brought into action by an abnormal condition of the paper web at one point in the machine for starting a break of the web at a preceding point in 15 the machine, and means controlled in its action automatically by the break-starting means for cutting the web longitudinally; whereby the web will be prevented from breaking clear through, and a lead strip will 20 be formed which will feed forwardly in the machine.
3. In a paper making machine, the combination of means brought into action by an abnormal condition of the paper web at one 25 point in the machine for rupturing the web at a preceding point in the machine, and web incising means controlled in its action automatically by the rupturing means for forming a lead strip on the paper web; whereby 30 the rupture will be prevented from developing clear across the web, and the lead strip will feed forwardly in the machine.
4. In a paper making machine, the combination of fluid jet means operable automatically to rupture the paper web at a given 35 point in the machine upon the accidental breakage of the web at a point beyond, and means controlled in its action by said fluid jet means for cutting the web longitudinally 40 at a point adjacent the rupturing action; whereby a lead strip will be formed on the web which will feed forwardly in the machine beyond the rupture point.
5. In a paper making machine, the combination of fluid jet means operable automatically to rupture the paper web at a given 45 point in the machine upon the accidental breakage of the web at a point beyond, and a second fluid jet controlled automatically in 50 its action by the rupturing jet and acting to incise the web longitudinally at a point preceding the rupture, to form a lead strip on the web.
6. In a paper making machine, the combination of means adapted to be brought into 55 action by an abnormal condition of the paper web at one point in the machine for starting a break of the web at a preceding point, means operated automatically by the break starting means for cutting the web longitudinally to 60 form a lead strip, and means for widening said lead strip to the full width of the web.
7. In a paper making machine, the combination of means adapted to be brought into 65 action by an abnormal condition of the paper
- web at one point in the machine for starting a break of the web at a preceding point, means operated automatically by the break starting means for cutting the web longitudinally to 70 form a lead strip thereon, and means for cutting the web transversely from the lead strip to widen the latter to the full width of the web, said transversely acting cutting means being adapted when positioned for action, to 75 render the lead strip cutter inactive.
8. In a paper making machine, the combination of a fluid jet means adapted to be automatically operated to direct its jet onto the paper web to rupture the same upon the accidental breakage of the web at a point beyond, a second fluid jet means movable to an active position to direct its jet onto the paper web to form a lead strip thereon, and means operated by the fluid supply of the first mentioned jet, for moving said second jet to active 80 position.
9. In a paper making machine, the combination of fluid jet means adapted to be operated automatically to rupture the paper web upon the accidental breakage of the web 85 at a point beyond, a second fluid jet means movable from an inactive position to an active position to form a lead strip on the paper web, and a third jet means operable on the paper web to widen said lead strip to the full width 90 of the web, said third jet means acting when positioned for operation, to automatically move the second jet means to inactive position.
10. In a paper making machine the combination of means for rupturing the paper web and adapted to be automatically brought into action by an abnormal condition of the web at a point in the machine beyond the rupturing point, a fluid jet nozzle located in the machine at a point adjacent the rupturing point and movable from an outer position directing its jet beyond the edge of the web, to an inner position to direct its jet onto the web to form a lead strip thereon, and means operated automatically by the web rupturing means to move said jet nozzle to its inner active position.
11. In a paper making machine, the combination of a fluid jet nozzle in position to direct 100 its jet onto the paper web, a normally closed valve controlling the supply of fluid to said nozzle, means operating on the accidental break of the web to open said valve, a second 105 jet nozzle adapted to be positioned to direct its jet onto the web at a point adjacent the impingement of the first mentioned jet to form a lead strip on the web, and means operating on the opening of the valve, to position said jet for action on the web.
- 120 In testimony whereof, I have affixed my signature hereto.

FRANK A. PESCHL.
